AUTOMATIC AND MANUAL CARBON DIOXIDE FIRE EXTINGUISHING SYSTEM INCLUDING SELECTOR VALVE

Scott E. Allen and Ozro N. Wiswell, Los Angeles, Calif., assignors, by mesne assignments, to C-O-Two Fire Equipment Company, Newark, N. J., a corporation of Delaware

Application July 1, 1929, Serial No. 375,032

6 Claims. (Cl. 169—11)

Our invention relates to a system for supplying a fire extinguishing medium to a compartment or room where there is a fire.

In this art, it is common practice to provide a source of fire extinguishing medium, such as CO₂ or any inert gas, and means, such as piping, for supplying the inert gas, when released, to a room. Where there is a plurality of rooms, the usual practice is to provide a separate system for each room.

An object of our invention is to provide a system for protecting a plurality of rooms in which a single source of fire extinguishing medium is connected to supply the several rooms.

Another object of our invention is to provide a system of this character in which the fire extinguishing medium may be selectively supplied to one or more rooms.

In our invention this object is accomplished by providing the system with a selector means interposed in the system between the source of fire extinguishing medium and the rooms.

A further object of our invention is to provide a system in which the fire extinguishing medium is released and the selector means is operated by the same controlling means.

This object is accomplished by connecting the selector means and the source of supply to the controlling means. In the preferred form of our invention the operating means automatically operates the selector means to permit fire extinguishing medium to be supplied to one or more rooms, and releases the fire extinguishing medium from the source of supply.

A further object of our invention is to provide a system in which a predetermined temperature in one of the rooms operates the selector means and releases the fire extinguishing medium so that the fire extinguishing medium passes only to the room where the fire is present.

A still further object of our invention is to provide a system which may be manually operated.

Further objects of our invention will appear hereinafter.

In the accompanying drawings, in which we have shown a preferred form of our invention,—

Fig. 1 is a view showing the arrangement of the apparatus of the fire extinguishing system of our invention.

Fig. 2 is an enlarged sectional view taken on the line 2—2 of Fig. 1 showing the releasing device of our invention.

Fig. 3 is a partial sectional view taken on the line 3—3 of Fig. 2.

Fig. 4 is an enlarged sectional view taken on the line 4—4 of Fig. 1, showing the selector valve of our invention.

Fig. 5 is a sectional view taken on the line 5—5 of Fig. 4.

In Fig. 1 of the drawings, we have shown a plurality of adjacent enclosures or rooms 11, 12 and 13 which are to be protected by a fire extinguishing system of our invention. Only three enclosures are shown, but additional enclosures 10 may be protected in a similar manner to those shown.

A supply of fire extinguishing gas or fluid such as CO₂ for extinguishing a fire in the enclosures is supplied under pressure in one or more bottle-shaped containers which may be disposed at a point remote from the enclosures, individual containers being designated as containers 15, 16, 17, 18, 19 and 20. Releasing means or control heads 22, 23, 24, 25, 26, and 27 are supplied with the containers for releasing the gas therefrom, each of the containers being supplied with one of the heads; for example, the container 15 is equipped with head 22, the container 16 with head 23, etc.

The heads on the containers are similar to the head shown in our co-pending application entitled "Non-stalling self-energizing head for puncturing closure disc", Serial No. 349,150, filed March 22, 1929. We have shown the details of one of the heads, head 22, in Figs. 2 and 3 for completeness, it being understood that all of the heads are similar to the one described. The container 15 to which the head is secured has an outlet opening 30 through an upper tapered portion 31 thereof, the opening 30 being closed by a penetrable diaphragm 32 secured in place by a plug 33 having a central opening 34 therethrough. There is also a relief port 30a leading outwardly from the opening 30 below the diaphragm 32, which port is normally closed by a safety disk 32a, the purpose of which will be explained hereinafter. Threadedly secured to the upper portion 31 of the container 15 by a union 36 is the head 22 which is composed of a body 37 having walls which form a cylinder 38.

Slidably positioned in the cylinder 38 is a piston 40 having a depending hollow pin 41, the lower edges of which are sharpened and positioned in the opening 34 so that a downward movement of the piston 40 moves the edges of the pin 41 downwardly and causes the pin 41 to penetrate the diaphragm 32 so as to release a fluid from the container 15.

A central opening 44 in the piston 40 communicates with an opening 45 in the interior of

the pin 41, and communicates with a space 46 above the piston 40 by means of openings 47 formed through the walls of the piston 40. A ball valve 48 is disposed in the opening 44 and permits passage of a fluid upward through the opening 45 to the space 46 but checks a reverse flow. Communicating with the space 46 is a discharge end 50 of an explosive plug 51 which is threadedly secured in the walls of the body 37. The explosive plug 51 has a charge of powder or other explosive material on the interior thereof which is ignited when electric power is supplied thereto. As best shown in Figs. 1 and 3, a discharge pipe 53 which is threaded in an opening in the body 37 opposite the explosive plug 51 is connected to a header pipe 54 and permits a fluid to pass from the space 46 to the header pipe 54. An interconnecting pipe 56 having an end threaded in the body 37 at right angles to the pipe 53 has an opposite end threaded in the head 23 adjacent the head 22 and permits communication between the space 46 in the head 22 with a similar space in the head 23. A pipe 57 threaded in the body 37 opposite the pipe 56 is connected to other apparatus as will be described later and is for the purpose of introducing a fluid to the space 46.

Secured to the piston 40 is a vertical rod 58 which is slidable in an opening 59 formed in the body 37 and has a manual operating handle 60 at the upper end thereof. Between the handle 60 and the body 37 is a spring 61 for normally maintaining the piston 40 in raised position.

The releasing head 22 of our invention is operated to release a fluid from the container 15 when the piston 40 is moved downward. This may be done manually by moving the handle 60 downward or by creating a gas pressure in the space 46 through the explosion of the explosive plug 51 or by introducing a gas through the pipes 53, 56, or 57. The gas is restrained from passing downward through the opening 45 by the ball valve 48 and the pressure thereof moves the piston 40 downward and causes the lower sharpened edges of the pin 41 to pierce the diaphragm 32. This releases the gas from the container 15 which gas passes upward through the openings 30 and 45, around the ball valve 48, through the openings 44 and 47 to the space 46 whence it may pass out through the pipes 53, 56 or 57.

As best shown in Fig. 1, the heads 23, 24, 25, 26 and 27 are respectively interconnected by interconnecting pipes 63, 64, 65 and 66 in a manner similar to that in which head 22 is connected to head 23, thus permitting communication between space 46 in the head 22 and similar spaces in the other heads. It should be noted that the interconnecting of the heads permits a fluid released from one of the heads to pass to the other heads and operate these heads. Discharge pipes 68, 69, 70, 71 and 72 of the heads 23, 24, 25, 26 and 27 respectively are connected to the header pipe 54 and permit fluid from the containers to pass to the header pipe 54, which pipe extends from a position adjacent the containers to a position adjacent the enclosures 11, 12 and 13.

Branching from the header pipe 54 are branch pipes 74, 75 and 76, supplied for the enclosures 11, 12 and 13 respectively, and the discharge ends thereof being closed by selector valves 78, 79 and 80 respectively. Outlet pipes 82, 83 and 84 from the selector valves pass into the enclosures through the walls thereof, where they are provided with distributing pipes 86, 87 and 88 for distributing the fire extinguishing gas to the enclosures.

We have shown the details of the selector valve 78 in Figs. 4 and 5, it being understood that the construction of the other selector valve is similar to the selector valve 78 described. The selector valve 78 consists of a valve body 90 having an interior opening 91 with which the branch pipe 74 and the outlet pipe 82 communicate. In the center of the opening 91 is positioned a wedge-shaped plug 94 which fits into a wedged-shaped opening formed in the walls of the valve body 90 in such a way as when seated to close communication between the branch pipe 74 and the outlet pipe 82. Formed in the valve body 90 above the plug 94 is a central opening 95 in which the plug 94 may be raised so as to permit communication between the branch pipe 74 and the outlet pipe 82. To the walls of the valve body 90 is threadedly secured a cylindrical member 96 having a lower horizontal wall 97 which closes the opening 95 and which has a central opening 98 which provides a guide for a vertical rod 100 secured at the lower end thereof to the plug 94.

The rod 100 passes upward through a central cylinder 101 formed by the walls of the cylindrical member 96 and has a piston 102 secured thereto, which piston 102 is slidable in the cylinder 101 as the valve 78 is opened and closed. Threadedly secured to the upper end of the cylindrical member 96 is a cap 103 which provides an opening through which the upper end of the rod 100 extends, the upper end of the rod 100 having a manual operating handle 104 secured thereto. Communicating with a space 106 below the piston 102 is an explosive plug 108 similar in construction to the explosive plug 51 of the head 22, and the discharge end of a pipe 109 which is connected to other apparatus in a manner described later, and which is for the purpose of supplying a fluid to the space 108.

The selector valve 78 is opened by manually raising the handle 104 or by creating a gas pressure in the space 106 by an explosion of the explosive plug 108 or by gas introduced through the pipe 109. This causes the piston 102 to be raised, raising the plug 94 and opening communication between the branch pipes 74 and the outlet pipes 82. When one of the selector valves is opened, a fluid from the header pipe 54 may pass therethrough to one of the enclosures. The selector valves thus form a means of selecting the enclosure to which the gas is introduced.

In order to provide a means for controlling the operation of the heads and the selector valves, we provide an automatic control system consisting of temperature-responsive elements or thermostats 112, 113 and 114, one of the thermostats being placed in each of the enclosures 11, 12 and 13 respectively. The thermostats are of a common type having electrical contacts that close when the temperature exceeds the setting thereof. The thermostat 112 forms a switch in a circuit consisting of a positive wire 116 and a negative wire 117 which connects a battery 118 or other source of power to the explosive plug 51 on the head 22. The thermostats 113 and 114 likewise form switches in circuits consisting of positive wires 120 and 121 and negative wires 122 and 123 which respectively connect the battery 118 to similar explosive plugs 125 and 126 on heads 23 and 24.

The explosive plug 108 of the selector valve 78 is connected in parallel with the explosive plug 51 by wires 127 and 128 so that when the circuit is completed from the battery 118 both explosive plugs 51 and 108 will explode. Similar ex-

5 explosive plugs 130 and 131 on the selector valves 79 and 80 are connected in parallel with explosive plugs 125 and 126 by wires 132, 133, 134 and 135. Connected in shunt with the thermostat 112 by wires 138 and 139 is a manually operated switch 140, similar switches 141 and 142 being respectively connected in shunt with thermostats 113 and 114 by wires 143, 144, 145 and 146. The system is automatically operated when the 10 temperature in one of the enclosures, for example, enclosure 11, exceeds a predetermined safe value. This causes the contacts of the thermostat 112 to close thus exploding the explosive plugs 108 and 51 which opens the selector valve 18 and operates the head 22 to release gas from the container 15. The gas from container 15 releases the gas in the other containers in a manner explained before, which gas passes to the header pipe 54, through the branch pipe 74, the 20 selector valve 78 and the distributing pipes 86 to the enclosure. Since only the selector valve 78 is opened, the gas is not admitted to the enclosures 12 and 13.

To supplement the automatic system, we provide a manual control system which consists of a supply of gas under pressure which is furnished in a container 150 equipped with a manually releasable valve on head 151, which may be similar to the heads already described if desired. The 25 container 150 is placed at a convenient place, and a discharge outlet thereof is connected to the pipe 57 of the head 22. The pipe 57 is connected by pipes 153, 154 and 155 to manually operable valves 157, 158 and 159, the valve 157 being connected to the pipe 109 of the selector valve 78 and similar pipes 160 and 161 connecting the valves 158 and 159 to selector valves 79 and 80 respectively.

When a fire occurs in an enclosure, as for example enclosure 11, the manual control system is operable by opening the valve 151 on the container 150, thus releasing the gas therefrom, and by opening the valve 157 associated with the enclosure 11 in which the fire is located. The gas 40 from the container 150 passes through the pipe 57 to the head 22 where the pressure thereof releases the gas as has been previously described. The gas also passes through the pipe 153 and the valve 157 to the selector valve 78 where the 45 pressure thereof opens the valve. Gas from the containers is thus admitted to the enclosure 11 in a manner previously described.

It should be noted that our fire extinguishing system may be operated by the automatic control as explained before, and may be operated manually in three ways. The first way of manually operating the system consists in depressing the operating handle on one of the heads and in raising the operating handle on one of the 50 selector valves. The second way consists in opening the valve 151 on the container 150 and in opening one of the valves 157, 158 or 159. The third way consists in closing one of the switches 140, 141 or 142 which produces an operation similar to the automatic operation. All of these operations act to introduce the gas into the enclosure in which the fire is located and to exclude it from all other enclosures.

The diaphragm 32 will withstand normal fluid pressures in the container, but the fluid pressure depends upon temperature and when exposed to high temperatures either due to abnormal weather conditions or to other causes, the fluid pressure would rise sufficiently to burst the diaphragm. The fluid then rushing into the con-

duit 54, which is normally closed by the selector valves, would then subject said conduit to abnormal strain unless some relief were provided therefor. To avoid this danger we have provided the safety port 30a which is closed by the disc 5 32a. The latter is designed to withstand normal fluid pressures in the container but will rupture at a predetermined pressure which is below the rupture point of the diaphragm 32. This permits the fluid to discharge into the open in case 10 the pressure rises to an abnormal point and protects the closed conduit system from bursting and causing probably serious damage.

It is obviously possible to make changes in our system without departing from the spirit of our invention, for example, it is possible to use a single selector valve with a plurality of enclosures and a single container in place of the plurality shown. These and other changes can be made without departing from the spirit of our invention.

We claim as our invention:

1. In a fire extinguishing system, the combination with a plurality of enclosures, of a gas supply means, a conduit system for leading gas 25 from the supply means to said enclosures, fluid pressure actuatable primary release means for releasing said gas from the supply means into the conduit system, a fluid pressure actuatable secondary release means for controlling the admittance of the gas from the conduit system into each of said enclosures, and control means for actuating the primary release means and coincidentally any or all of the secondary release 30 means to admit the gas to one or more of said 35 enclosures, the control means including a container carrying a fluid under pressure, and means for admitting fluid from the container to the primary release means and selectively to any of the secondary release means to operate the same. 40

2. In a fire extinguishing system the combination with a plurality of enclosures, of a container holding a fire extinguishing medium under pressure, a conduit system for leading said medium from the container to said enclosures, fluid pressure actuated primary release means for releasing said medium from the container into the conduit, a secondary release means for controlling the admittance of said medium from the conduit into each of said enclosures, and a control for coincidentally actuating said primary release means and any or all of said secondary release means whereby said fire extinguishing medium is admitted to one or more of said enclosures, the control means including an auxiliary container holding fire extinguishing medium under pressure, and means for conducting such fire extinguishing medium from the auxiliary container to one or more of the secondary release means and simultaneously to the primary 50 release means to actuate the same and to be released together with the medium from the first named container into the conduit system. 55

3. In a fire extinguishing system the combination with a plurality of enclosures of a plurality of containers each holding fire extinguishing fluid under pressure, a conduit system for leading said fluid from the containers to the enclosures, control means individual to each enclosure for controlling the admission of the fluid from the conduit into each of said enclosures, a fluid pressure actuated discharge head for each container adapted upon actuation to discharge fluid from the container into said conduit system, fluid conducting means interconnecting the 75

heads whereby all of the heads will be actuated upon actuation of any one of them, there being a discharge head individual to each enclosure and means controlled by thermal conditions in each 5 enclosure for actuating the discharge head individual thereto and simultaneously actuating the control means individual to said enclosure.

4. In a fire extinguishing system, the combination of: a plurality of enclosures, a container 10 holding a fire extinguishing medium under pressure, conduit means for leading fire extinguishing medium from said container to the enclosures, a primary release means for releasing said fire extinguishing medium into the conduit 15 means, a fluid pressure actuated secondary release means for controlling the admittance of said fire extinguishing medium from the conduit means to each of said enclosures, a control for coincidentally actuating said primary release 20 means and any or all of the secondary release means whereby said fire extinguishing medium is admitted to one or more of said enclosures, an additional control including an auxiliary container holding a fire extinguishing medium 25 under pressure, and means for conducting the said medium from the auxiliary container selectively to one or more of the secondary release means to actuate the latter and to then be admitted into the enclosure or enclosures so selected.

5. In a fire extinguishing system, the combination of: a plurality of enclosures, a container holding a fire extinguishing medium under pressure, conduit means for leading the medium from 30 said container to the enclosures, a fluid pressure actuated release means for releasing said medium into the conduit means, fluid pressure ac-

tuated selector means for controlling the admittance of said medium from the conduit means to said enclosures selectively, and a control for coincidentally actuating said release means and the selector means whereby said medium is admitted to one or more of said enclosures, said control comprising an auxiliary container holding a fire extinguishing fluid under pressure, and means for conducting said fluid to said release means and selectively to the selector means to 10 actuate the same and then be admitted into the enclosure or enclosures so selected. 5

6. In a fire extinguishing system, the combination of: a plurality of enclosures, a container holding fire extinguishing medium under pressure, conduit means for leading the medium from said container to the enclosures, fluid pressure actuated primary means for releasing said medium from said container into the conduit means, fluid pressure actuated secondary release 20 means for controlling the admittance of said medium from the conduit to each of said enclosures, and a control for actuating said primary release means and any or all of said secondary release means whereby said medium is conducted to one or more of said enclosures, the control including an auxiliary container holding a fire extinguishing fluid under pressure, means for conducting a portion of said fluid to the primary release means to actuate the same and 25 to then pass to the secondary release means, and means for conducting another portion of the fluid to the secondary release means to actuate the same and then be admitted to the enclosure or enclosures so selected. 30 35
